UNITED STATES PATENT OFFICE

125,752

DESIGN FOR A BELT ATTACHMENT FOR ARTIFICIAL LEGS

Emmett Blevens, Louisville, Ky.

Application March 8, 1940, Serial No. 90,771

Term of patent 14 years

To all whom it may concern:

Be it known that I, Emmett Blevens, a citizen of the United States and a resident of Louisville in the county of Jefferson and the State of Kentucky, have invented a new, original, and ornamental Design for a Belt Attachment for Artificial Legs, of which the following is a specification, reference being had to the accompanying drawing, forming a part thereof.

Fig. 1 is a perspective view of the side and

edge of a belt-attachment for artificial legs, embodying my new design;

Fig. 2 is an outer side elevational view thereof; Fig. 3 is an edge elevational view thereof; and Fig. 4 is an inner side elevational view of the same.

I claim:

The ornamental design for a belt attachment for artificial legs, as shown.

EMMETT BLEVENS.
